(57) **CLAIM**

The ornamental design for a handlebar mount for a motorcycle meter, as shown and described.

DESCRIPTION

FIG. 1 is a perspective view of a handlebar mount for a motorcycle meter showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a back view thereof; and,

FIG. 8 is another perspective view wherein the broken lines show a handlebar and meter to which the mount is connected. The broken-line components are shown for the purpose of illustrating environmental structure and form no part of the claimed design.
